UNITED STATES PATENT OFFICE.

NOYES PALMITER, OF SCOTT, NEW YORK.

IMPROVED WASHING-MACHINE.

Specification forming part of Letters Patent No. **67,575**, dated August 6, 1867.

To all whom it may concern:

Be it known that I, NOYES PALMITER, of SCOTT, in the county of Cortland, and in the State of New York, have invented certain new and useful Improvements in Washing-Machines; and I do hereby declare that the following is a full, clear, and exact description thereof, reference being had to the accompanying drawings, and to the letters of reference marked thereon, making a part of this specification.

In the annexed drawings, A represents an oblong box, having suitable feet, upon which it is supported. The bottom of this box is provided with three or more slots, *z z z*, running along the entire length, upon which are placed crosswise a series of ribs, *a a*. These ribs, being placed at short intervals apart, allow the water to pass between and under them and cause the clothing to be thoroughly soaked.

E E represent two standards placed at each side of the box, having a cross-bar, *h*, at the top, from which is suspended the wash-board. The under part of the wash-board is also provided with slats and ribs *a' a'*, in a manner similar to the bottom of the box, and is connected to suitable arms B B, which are suspended from the cross-bar *h*. The top parts of the arms B have long tenons, which pass into the openings made therefor in the bar *h*, and are rounded at the bottom to correspond with the rounded tops of the connecting-boards *c c*. It will be seen that the tops of these boards *c* are so cut, and the bottoms of the arms B likewise, as to form a neat joint when they are connected by the cross-piece *f*.

Upon one end of the box A is a short shaft,

S, having suitable bearings, and a crank, *l*, at the outer extremity. Upon the inner end of this shaft is a faced cog-wheel, F, which meshes into a small beveled cog, *m*, having a crank, P, Figure 1, connected to its under side, and to which is passed a pitman, *g*, to the cross-piece *f* of the wash-board *b*, whereby the said board is propelled back and forth over the ribs in the box A.

By means of the long tenons *d* at the upper part of the arms B the board is made to suit the quantity of clothing placed within the box, and the joint at *f* allows the board to be propelled in horizontal manner. The board can be thrown upward from the box and out of the way by uncatching the pitman and throwing the arms up by the tenons on the upper bar, *h*.

Having thus fully described my invention, what I claim as new, and desire to secure by Letters Patent, is—

1. The arrangement of the box A, with its slots *z z* and ribs *a a a*, when used in combination with the board *b* with slots and ribs *a'*, in the manner and for the purposes specified.
2. The arms B B, constructed as described, and connected to the wash-board, when operated by means of the shaft S, wheels F *m*, crank *p*, and pitman *g*, when combined and used for the purposes set forth.

In testimony that I claim the foregoing I have hereunto set my hand this 1st day of April, 1867.

NOYES PALMITER.
